HEATING PLUG

Richard A. Siegler, Oak Park, Ill.

Application July 9, 1938, Serial No. 218,372

7 Claims. (Cl. 219—41)

This invention relates to a heating plug and particularly to that type of heating plug which may be used in connection with a hot water bottle or other liquid container so as to heat the container and its contents.

It has for one object to provide a device of the type indicated which is simple in construction and economical in operation.

Another object is to provide such a device so arranged that it can be readily assembled, and in case of damage or wear can be readily repaired.

Another object is to provide the device indicated so arranged that the heating element itself is shielded from the liquid but circulation of the liquid past the heating element is provided, and hence more effective heating of the fluid is accomplished.

Other objects will appear from time to time in the course of the specification and claims.

The invention is illustrated more or less diagrammatically in the accompanying drawing, wherein:

Figure 1 is a side elevation;

Figure 2 is a longitudinal section on an enlarged scale taken at line 2—2 of Figure 1; and

Figure 3 is a transverse sectional detail taken at line 3—3 of Figure 2.

Like parts are indicated by like symbols throughout the specification and drawing.

1 indicates generally the body of the housing of the device and as shown it is preferably made of insulating or non-conductive material. It may be threaded at its upper margin as at 2 to receive a correspondingly threaded enclosing member 3, which may be reduced as at 4 if desired, and perforated as at 5 to permit the conduit 6 to pass through it.

The member 1 is preferably provided with a hollow portion 7 within which are located some or all of the electric connections. As illustrated herewith, three thermostatic elements 8, 9 and 10 are shown, one or another of which may be connected to the central contact member 11. Wires 12, 13 and 14 are connected with the thermostats 8, 9 and 10 respectively. The details of the thermostatic arrangement form no essential part of the present invention and will not be more fully described. The invention relates more particularly to the construction of the device rather than to the electrical connections and might be applied equally well to an apparatus which did not have any thermostatic arrangement.

The body 1 is provided with a reduced extension 15, which is exteriorly threaded as at 16 if desired, and is provided with a hollow portion 17.

Preferably molded in the extension 15 and lining a portion of the hollow 17 is a cap or closure member 18 which at its upper end has a laterally extending flange 19 which is engaged in the body of the material which forms the part 1. As indicated, it is preferably molded in that manner. It is closed at its outer end by the integral bottom portion 20. The body 15 is hollowed out as at 21. A shell 22 lies within the hollowed out portion and may, as indicated in Figure 1, extend into the body of the member 15. It is preferably perforated as at 23, 23 and its end is open as at 24. As indicated, it is positioned about the cap member 18 and extends downwardly beyond it, but because its end is open and because it is provided with a plurality of perforations 23, fluid may circulate freely inside the member 22 and between it and the cap 18 and about the latter.

A supporting member 25, which may be of insulating material, is supported upon the part 11 and extends downwardly through the cavity 17 and into the cap member 18. Fixed upon it is an enlarged supporting member 26. A wire 27 leads from the contact member 10 and is wrapped about the support 26 as shown. This wire forms the heating element. At its other end it passes upwardly and is connected as at 28 to an incoming wire 29.

Nothing is shown of the details of the wiring mechanism and these details form no part of the present invention, which may be embodied in any construction in which means are provided for a heating element and suitable electric connections to bring current to that element.

I claim:

1. In a heating plug, a body portion, a cavity formed in said body portion, and a closed cap member in communication with said body portion and extending outwardly beyond the said body portion, an annular end extension of insulating material formed on said body and extending outwardly along and spaced away from said cap, and a hollow shell positioned partially within said body, partially within said annular extension, and extending outwardly beyond said cap, said shell having its exposed end open and being perforated, and a heating element positioned within said cap.

2. In a heating plug, a body portion, a cavity formed in said body portion, and a closed cap member in communication with said body portion and extending outwardly beyond the said body portion, an annular end extension of insulating material formed on said body and extending outwardly along and spaced away from said cap, and a hollow shell positioned partially within said cap.

- body, partially within said annular extension, and extending outwardly beyond said cap and beyond said extension, said shell being perforated in its side and having an open end, and a heating element positioned within said cap.
3. In a heating plug, a body portion formed of insulating material, said body portion shaped to provide an internal cavity, electrical connection members positioned within said cavity, an additional longitudinal cylindrical cavity formed in said body portion and communicating with said first mentioned cavity, and a closed cap member in communication with said body portion and extending outwardly beyond the said body portion, an annular end extension formed on said body and extending outwardly along and spaced away from said cap, and a hollow shell positioned partially within said body, partially within said annular extension, and extending outwardly beyond said cap, said shell being freely perforated in its side with a plurality of perforations and having an open end, and a heating element positioned within said cap.
4. In a heating plug, a body portion, electrical connections extending thereto, a closed shell joined to and extending outwardly beyond said body portion, a heating element therein, and a second member positioned about and spaced away from said first mentioned shell extending outwardly beyond its end, and providing about it an annular circulation space, a plurality of openings in said second member, said shell and said second member extending from said body portion a distance less than the length of said body portion.
5. In a heating plug, a body portion, electrical connections, a closed shell joined to and extend-

ing outwardly beyond said body portion, a heating element therein, and a second member positioned about and spaced away from said first mentioned shell extending outwardly beyond its end, and providing about it an annular circulation space, and openings in the sides and in the end of said second member, said shell and said second member extending from said body portion a distance less than the length of said body portion.

6. In a heating plug, a body portion, electrical connections, a closed metallic shell joined to and extending outwardly beyond said body portion, a heating element therein, and a second metallic member positioned about and spaced away from said first mentioned metallic shell and extending inwardly beyond its end, and providing about it an annular circulation space, openings in said second member, said shell and said second member extending from said body portion a distance less than the length of said body portion.

7. In a heating plug, a body portion, electrical connections, cavities formed therein, a closed shell joined to and extending outwardly beyond said body portion a distance less than the length of said body member, a heating element therein, the inside of said shell in communication with one of said cavities, and a second member positioned about and extending inwardly beyond the end of and spaced away from said first mentioned shell, and providing about it an annular circulation space, and openings in the sides and in the end of said second member, said shell and said second member extending from said body portion a distance less than the length of said body portion.

RICHARD A. SIEGLER.
